UNITED STATES PATENT OFFICE

158,780

MONOGRAMMING MACHINE

Sam H. Meister, Shaker Heights, Ohio, assignor,
by mesne assignments, to Meistergram Cor-
poration, Cleveland, Ohio, a corporation of Ohio

Application August 15, 1949, Serial No. 4,510

Term of patent 14 years

(Cl. D64—11)

To all whom it may concern:

Be it known that I, Sam H. Meister, a citizen of the United States and a resident of Shaker Heights, in the county of Cuyahoga and State of Ohio, have invented a new, original, and ornamental Design for Monogramming Machine, of which the following is a specification, reference being had to the accompanying drawing, forming a part thereof, in which:

Fig. 1 is a front perspective view of a monogramming machine, showing my new design.

Fig. 2 is a rear perspective view of the machine shown in Fig. 1.

I claim:

The ornamental design for a monogramming machine, substantially as shown.

SAM H. MEISTER.
